DESIGN FOR A PERFUME BOTTLE CONTAINER

Jacques Guerin, Paris, France

Application October 15, 1938, Serial No. 80,468

Term of patent 7 years

To all whom it may concern:

Be it known that I, Jacques Guerin, a citizen of the Republic of France, residing in Paris, France, have invented a new, original, and ornamental Design for Perfume Bottle Containers, of which the following is a specification, reference being had to the accompanying drawing, forming part thereof.

In the drawing:

Fig. 1 is a front elevation of a perfume bottle container showing my new design;

Fig. 2 is a rear elevation of the perfume bottle container;

Fig. 3 is a side elevation of the said container viewed from the right; and

Fig. 4 is a top plan view thereof.

The characteristic features of the design reside in the shape of the container, in the solid color of the outside of the container which is broken by a contrasting multi-colored winding ribbon on its surface and also by the contrasting color of the inside of the container visible through the opening in the front of said container.

I claim:

The ornamental design for a perfume bottle container substantially as shown and described.

JACQUES GUERIN.
